UNITED STATES PATENT OFFICE.

ALEXANDER JAMESON, OF INDIANAPOLIS, INDIANA.

DENTAL APPARATUS.

936,539.

Specification of Letters Patent. Patented Oct. 12, 1909.

Application filed October 25, 1907. Serial No. 392,153.

To all whom it may concern:

Be it known that I, ALEXANDER JAMESON, a citizen of the United States, residing at Indianapolis, in the county of Marion and State of Indiana, have invented certain new and useful Improvements in Dental Apparatus, of which the following is a specification.

The object of my invention is to produce a means for facilitating the formation of dental matrices, especially for the production of metal inlays, the structure being especially designed for use in connection with the casting apparatus forming the subject-matter of my pending application, Serial No. 381,416, but of course, not being limited to such use.

The accompanying drawings illustrate my invention.

Figure 1 is a perspective view of the apparatus embodying my present invention; Fig. 2 a side elevation showing the parts inverted for the application of the first or preliminary investiture; Fig. 3 a sectional detail showing the complete investiture with the parts ready for withdrawal of the sprue former; Fig. 4 a perspective detail of means for holding a plurality of wax casts whereby a multiplicity of castings may be made in a single investiture; Fig. 5 a sectional detail of a multiple investiture; Fig. 6 an enlarged sectional detail of the multiple pattern holder; Fig. 7 a sectional detail showing a form in which the various modifications are combined; Fig. 8 a perspective of a modified sprue, and Fig. 9 a section detail of the form shown in Fig. 8.

In the drawings, 10 indicates a suitable base having a socket 11 adapted to receive temporarily the investiture cup 12. Rising from the base 10 is a standard 13 in the upper end of which is journaled a fork 14, the stem 15 of said fork passing through standard 13 and a light spring 16 arranged thereon so as to hold the spud 14' of the fork in a corresponding groove formed in the adjacent face of the standard 13. Passing through fork 14 is a stem 17 which, in Figs. 1 and 2 is shown as provided with a head 18 which limits the movement of stem 17 through fork 14. A suitable clamping screw 19 is provided by means of which stem 17 may be clamped in fork 14 at any desired position.

In Figs. 1, 2, and 3 I show stem 17 provided at one end with a sprue pattern 20 which in general is conical with a blunt tip

upon which the wax pattern 21 may be readily temporarily stuck. Referring particularly to the form shown in Figs. 1 to 3, the operation is as follows: With the parts in the position shown in Fig. 2, a preliminary plastic investiture 23 may be readily placed by a small brush around the pattern 21. Thereupon fork 14 is turned through half a turn to the position shown in Fig. 1. The cup 12 is then filled or nearly filled with plastic investiture 24, such for instance as plaster of paris or any other well known composition now commonly in use among dentists. Stem 17 is then lowered through fork 14 so as to project pattern 21 and the preliminary investiture 23, and sprue pattern 20 into the plastic in the cup 12, the head 18 forming a gage for the downward movement of stem 17. The parts are allowed to remain in this position until the plastic 24 has sufficiently hardened, whereupon, by turning stem 17 on its axis, the sprue may be readily disengaged from the pattern and plastic and withdrawn, whereupon the cup 12 with its contents is subjected to a sufficient degree of heat to melt the wax pattern 21 and allow the wax to either run out of the investiture or be absorbed thereby in the usual well known manner. Thereupon the cavity in the investiture may be filled with molten metal in any desired manner.

In order to facilitate the attachment of the patterns I have provided the peculiar form shown in Figs. 4 to 6. In this form the sprue pattern 20' is provided at its end with a socket 26 into which are permanently fastened by solder 27 or otherwise comparatively small wires 28, the ends of which are coated with a heavy coating of wax 29. With this form as many coated wires 28 as may be desired may be secured in the tip of the sprue pattern 20', and the wax patterns 21 readily stuck upon the wax 29, one pattern upon each finger 28-29. Each pattern may then be separately invested in a preliminary investiture 23 and the whole invested in the plastic 24, as already described. As soon as the plastic 24 is hardened the sprue pattern 20' may be readily detached by heating. When the cup is subjected to heat the wax not only of the patterns 21 but also of the channel formers 28-29 will be absorbed by the investiture, or will run out, and the sprue pattern 20' with its wires 28 may be then readily withdrawn, said wires lying freely within the channels formed by

the larger wax coating and these channels formed by the members 28-29 form sprue passages to the several cavities.

If desired, in order to make a neat job quickly, the sprue pattern may be provided with cutting fingers 30 which extend across the top of the cup 12 so that, when the stem 17 and attached sprue pattern are rotated, the fingers 30 will serve to trim any surplus 10 from the upper end of the plastic 24.

In the form shown in Figs. 8 and 9, the sprue 20" is similar to sprue pattern 20' except that it has a central bore 35. In the use of this sprue pattern I take a fine wire 15 36 and double it so as to form a loop 37 which, when slightly heated, may be driven into the pattern 21 and the wire then passed through the bore 35 and held by the fingers of the operator so as to hold the patterns 20 21 against the tip of the sprue pattern until the preliminary investiture has been placed about it. The wire 36 then may readily be withdrawn or allowed to remain until the final investiture and removal of the 25 sprue pattern.

I claim as my invention:

1. A dental apparatus comprising a base adapted to receive and support an investiture cup, the said cup, a standard carried by 30 said base, an arm rotatably mounted in said standard, and a sprue pattern having a stem slidably mounted in said arm, substantially as described.

2. A dental apparatus comprising a support, a stem mounted in said support and movable therein both axially and rotatively, a sprue-pattern axially mounted on said stem, a wire carried by the end of the sprue-pattern and having a fusible coating to 40 which a fusible pattern may be stuck, and an investiture cup to coöperate with said sprue-pattern.

3. A dental apparatus comprising an investiture cup, a sprue pattern having a stem, 45 a support for said stem through which it may be moved toward and from the investiture cup, and a wire carried by the end of the sprue-pattern and having a fusible coating to which a fusible pattern may be stuck.

4. A dental apparatus comprising a base adapted to receive and support an investiture cup, the said cup, a standard carried by 50 said base, an arm rotatably mounted in said standard, a sprue pattern having a stem slidably mounted in said arm, and a wire carried by the end of the sprue-pattern and having a fusible coating to which a fusible pattern may be stuck.

5. A dental apparatus comprising an investiture cup, a sprue pattern having an axial stem, a support for said stem through 60 which it may be moved toward and from the

investiture cup in which it may be rotated, cutter arms carried by the sprue pattern near its outer end and adapted to extend 65 across the mouth of the investiture cup.

6. A dental apparatus comprising an investiture cup, a sprue pattern having a stem, a support for said stem through which it may be moved toward and from the investiture cup, cutter arms carried by the sprue pattern near its outer end and adapted to extend 70 across the mouth of the investiture cup.

7. A dental apparatus comprising a base 75 adapted to receive and support an investiture cup, the said cup, a standard carried by said base, an arm rotatably mounted in said standard, a sprue pattern having a stem slidably mounted in said arm, cutter 80 arms carried by the sprue pattern near its outer end and adapted to extend across the mouth of the investiture cup.

8. In a dental apparatus, a sprue pattern comprising a main substantially conical body with a transversely extending cutter near its base.

9. In a dental apparatus, a sprue pattern comprising a main substantially conical body, an axial stem by means of which it 90 may be rotated, and a transversely extending cutter at the base of the sprue pattern.

10. In a dental apparatus, a sprue pattern comprising a substantially conical main body, and a wire extending from the apex 95 thereof and coated with a fusible coating.

11. In a dental apparatus, a sprue pattern comprising a substantially conical main body and a plurality of divergent wires detachably mounted in the apex of the main 100 body and each coated with a fusible coating to which patterns may be stuck.

12. In a dental apparatus, a sprue pattern comprising a substantially main conical body having a longitudinal bore, and a wire 105 doubled upon itself and having its doubled portion passed through the bore of the sprue pattern and projecting from the small end thereof for the purpose set forth.

13. In a dental apparatus, a sprue pattern 110 comprising a substantially main conical body having a longitudinal bore, and a holding wire extended through said bore and withdrawable outwardly therefrom and having an end adapted to be inserted into a pattern, for the purpose set forth.

In witness whereof, I have hereunto set my hand and seal at Indianapolis, Indiana, this twenty-first day of October, A. D. one thousand nine hundred and seven.

ALEXANDER JAMESON. [L. S.]
